PHOTOELECTRIC TUBE

Everett H. Bickley, Bala Cynwyd, Pa.

Application July 6, 1939, Serial No. 282,972

3 Claims. (Cl. 250—165)

The present invention relates to light sensitive apparatus and more particularly to photoelectric tubes of the electron emissive type.

Some of the objects of the present invention are to provide an improved photoelectric tube; to provide a photoelectric tube wherein a novel construction affords an extremely efficient electrical bond between the cathode conductor and the cathode lining of the tube at all times and one which does not deteriorate in use; to provide a simple and inexpensive tube construction whereby the tube and its associated internal parts can be easily and accurately assembled; to provide a contact spot of conducting material on the inner wall of a tube in position to be engaged by a cathode contactor acting under pressure; to provide a self-adjusting cathode contactor which, in assembly, requires only correct positioning for perfect contact operation; to provide means to uniformly deposit the cathode coating or lining on the inner wall of a tube; to provide means for forming a contact between a cathode contactor and the cathode coating of a photoelectric tube after the coating has been deposited on the tube; to provide a novel flag for so vaporizing and discharging electron emitting material that a more effective light sensitive lining is deposited on the inner wall of a tube; and to provide other improvements as will hereinafter appear.

In the accompanying drawing Fig. 1 represents a side elevation, partly broken away, of a photoelectric tube embodying one form of the present invention; Fig. 2 represents a perspective of the tube and the assembly of electrodes as prepared for insertion in the tube for sealing therein; Fig. 3 represents a section on line 3—3 of Fig. 2; Fig. 4 represents a section on line 4—4 of Fig. 1; Fig. 5 represents a perspective of the flag or electron active material receptacle as initially stamped for use; Fig. 6 represents a section of the complete flag as closed to retain the active material; Fig. 7 represents a fragmentary side elevation, partly broken away, of the tube of Fig. 1 showing a modified form of the invention with the cathode contactor as supported during the depositing of the cathode coating; Fig. 8 represents a section on line 8—8 of Fig. 7; and Fig. 9 represents a section on line 8—8 of Fig. 7 but showing the cathode conductor released to contact position. Figs. 3, 5 and 6 are on an enlarged scale for better illustration.

Referring to the drawing one form of the present invention comprises a glass body 10 of generally cylindrical shape which is open at one

end in order to receive an electrode assembly 11. This latter consists of a glass closure 12 arranged to fit within the open end of the body 10 to seal the same and is preferably formed with an annular flange 13 to contact with the circumferential marginal edge of the open end of the body 10. This closure is assembled with an anode rod 14 molded therein and welded to a terminal wire 15 which projects from the flanged end for attachment to the proper prong 16 carried by the base 17 of the completed tube. Also molded therein is a cathode conductor 18, one end of which is welded to a terminal wire 20 leading through the flanged end for attachment to a second prong 21 carried by the base 17 and spaced from the prong 16. The other end of the conductor 18 is welded or otherwise electrically bonded to two cathode forming contactors 22 which are of a length to extend well into the body 10, when assembled, and each of which terminates in an L-shaped offset to provide an effective contact foot 23. These contactors 22 are of spring material and are so disposed that when inserted within the body 10 each foot 23 will not only seat upon the inner wall of the body 10 but, due to the angular disposition of the contactors 22, will place the spring material under such tension as will press the feet 23 constantly against the aforesaid wall. The closure 12 is also provided with a glass exhaust pipe 24 extending axially exterior thereof between the terminals 15 and 20 so that the assembled tube can be evacuated and the pipe 24 sealed at the proper time by the application of a torch flame.

For the purpose of ensuring such an electrical bond between the feet 23 and the lining 25 of metal deposited upon the inner wall of the body 10, a deposit 26 of a graphitic compound is attached to the said wall at a location to register with the position of the feet 23 when the contactors 22 are located in proper assembled position. While graphite preferably forms the base of the aforesaid compound the invention is not so specifically limited because any other material may be used which does not have the characteristic of absorbing gases and then giving them off to the detriment of tube action.

In order to effect a uniform application of the metallic lining a novel flag has been devised comprising a metal stamping or otherwise formed rectangular piece 27 provided with two outwardly pressed pockets 28 each of which is formed with a through port 30. These pockets 28 are equally spaced from a transverse median line 31 about which the piece 27 is reversely bent in the direc-

tion to bring the mouths of the pockets 28 into juxtaposition to thereby encase the electron emissive pellet 32. With this operation completed the free ends of the piece 21 are overlapped and laterally bent to provide a tab 33 which is designed to seat against the anode rod 14 and be welded thereto. The assembled relation of the rod 14 and flag is such that the ports 30 are in close proximity to the longitudinal axis of the body or tube 10 and by reason of the back to back construction one port 30 discharges substantially axially toward one end of the body 10 and the other port 30 discharges substantially axially toward the opposite end. These discharges have a wide angle of distribution and result in an extremely accurate uniform deposited lining.

As a means for preventing stray current or short circuiting between the anode 14 and the lining 25, a relatively short sleeve 34 of glass or other non-conductor is slipped over the anode 14 to seat against the face of the closure 12 and to which it becomes attached when the closure is heated for sealing or other purpose. This sleeve 34 has a bore of sufficient diameter to provide a circumferential clearance about the anode 14 which serves effectively to interrupt any current attempting to reach the lining 25.

In assembling the parts the body 10 with its deposit 26 properly attached to the inner wall is ready to receive the electrode unit and this therefore is inserted through the open end of the body, care being taken that the cathode spring wires are longitudinally alined with the deposit 26. When the unit reaches the place where the flange 13 abuts the annular end of the body 10, the feet of the cathode contactors rest upon the deposit 26 and firmly seat thereon by reason of the pressure of the deformed spring conductors. The flange 13 is now fused into sealing relation with the tube body 10 and thereafter the tube is evacuated by means of the exhaust pipe 24. By now heating the internal metal parts by electrical induction the active material is vaporized and discharges in opposite directions from the flag to meet the cold inner wall of the body 10 and condense thereon in form of a relatively thin metallic lining of substantially uniform thickness. The exhaust pipe 24 can now be sealed by a torch flame properly directed. In the absence of the deposit 26 of conducting material the region adjacent the feet 23 would be bare of lining deposit due primarily to heat dissipated by the cathode wires under the bombarding of the flag. Any such disadvantage is overcome because of the deposit 26 which even though sparsely coated still maintains a perfect conducting relation between the springs and the lining. Following the formation of the lining, a portion of the tube is subjected to a heating flame at the proper place to burn off sufficient of the lining to form a window 35 for the admission of the light rays by which the tube action is controlled. The "flaming" may be avoided by using an anode of suitable size and a deflection of the vapor will be caused during bombardment, thus preventing condensation of the vapors on the glass where the window is desired.

In the form of the invention shown in Figs. 7, 8 and 9, a high resistance wire 36, such as

nickel of minute cross-section, is welded or otherwise made fast to the anode 14 and is formed with a laterally bent end 37 at such a distance from the anode 14 as will support the cathode contactors 22 out of contact with the wall of the tube 10. Thus when these contactors 22 are held by the hook-like end 37 each will be bowed inwardly with increased spring tension and the area of the glass opposite the cathode feet will therefore be exposed to the bombardment and be coated the same as the rest of the wall.

When the cathode coating is complete an electric current, either alternating or direct, is directed through the wire 36 to heat it to such incandescence as will result in the pressure of the spring contactors 22 bending the hook end 37 outwardly to a position where the contactors 22 are released and jump into contact pressing relation with the cathode coating. In this way a perfect contact is obtained and maintained with the cathode.

It will now be apparent that a photoelectric tube has been devised wherein provision is made for uniformly depositing a cathode coating on the interior of the tube and with which a novel means of forming a cathode contact is employed to give highly satisfactory and efficient results.

Having thus described my invention, I claim:

1. A photoelectric tube comprising an evacuated transparent body including a closure, a conductor passing through said closure and terminating in an anode, a second conductor passing through said closure and terminating in a spring contact tensioned in contact with the inner wall of said body, a cathode formed by a metallic lining deposited on said inner wall, and a spot of graphite compound deposited on said inner wall to form an electrical bonding bridge between said cathode and said spring contact, whereby electrical contact between said spring contact and said cathode is independent of physical contact between said contact conductor and said cathode.

2. A photoelectric tube comprising an evacuated glass body, a deposit of conducting material segregated as a relatively small spot on the inner wall of said body, a window forming metallic cathode deposited directly upon said glass body as an inner lining and overlapping said spot deposit to form an electrical bond therewith, a conductor leading axially from the exterior of said body to the interior thereof, said conductor terminating in a contactor spring pressed into electrical contact with said deposit, an anode in said body, and a conductor leading axially from said anode to the exterior of said body.

3. A photoelectric tube comprising an evacuated glass body, a deposit of a graphitic compound on the inner wall of said body, said deposit being segregated as a relatively small spot, a window forming metallic cathode deposited directly upon said glass body as an inner lining and overlapping said spot deposit to form an electrical bond therewith, a conductor leading axially from the exterior of said body to the interior thereof, said conductor terminating in a contactor spring pressed into electrical contact with said deposit, an anode in said body, and a conductor leading axially from said anode to the exterior of said body.

EVERETT H. BICKLEY.
